UNITED STATES PATENT OFFICE.

MORTON WALLACE GEARY, OF LOCK HAVEN, ASSIGNOR OF ONE-HALF TO
JOHN D. BROWN, OF SNOW SHOE, PENNSYLVANIA.

WATCH-KEY.

SPECIFICATION forming part of Letters Patent No. 339,875, dated April 13, 1886.

Application filed November 6, 1885. Serial No. 181,050. (No model.)

To all whom it may concern:

Be it known that I, MORTON WALLACE GEARY, a citizen of the United States, residing at Lock Haven, in the county of Clinton 5 and State of Pennsylvania, have invented a new and useful Improvement in Watch-Keys, of which the following is a specification, reference being had to the accompanying drawings.

10 My invention relates to watch-keys, the object being to provide a device of this character whereby a watch may be wound without removing the hand from the key or the key from the key-post of the watch, and to provide 15 a key which will fit posts of different sizes and will be thoroughly dust-proof.

With these ends in view the invention consists in the combination, with an outer casing or tube having a series of ratchet-teeth at its 20 lower end, of an interior casing carrying mechanism, and a collar rigidly connected with the interior tube, and having a series of ratchet-teeth to engage the teeth on the outer casing.

25 The invention further consists in the improved construction and combinations of parts hereinafter fully described, and pointed out in the claims.

In the drawings, Figure 1 is a side elevation 30 of a watch-key constructed in accordance with my invention. Fig. 2 is a vertical section of the same, and Figs. 3, 4, and 5 are detail views of parts detached.

In the accompanying drawings, in which 35 like letters of reference indicate corresponding parts in all the figures, A represents an outer tube or casing, which is formed at its lower end with a series of ratchet-teeth, a.

B represents an inner tube or casing, which 40 is fitted in tube or casing A so as to turn loosely therein, and is rigidly connected with a collar, C, which is fitted on the lower end thereof below casing A, said collar having a series of ratchet-teeth, b, upon its upper end, 45 which are adapted to engage with the teeth a. The collar C is fitted upon the tube or casing B, and held by a transverse pin or rivet, c.

Within the inner casing, C, are arranged the 50 clamping-jaws D, which are convex on their inner faces, so that when they are lowered they

will be spread apart by the pin or rivet c, which fits between said jaws. The outer sides of said jaws are concave, so that they may be spread or opened to their fullest extent without coming in contact with the inner casing. 55

Upon the inner side of the outer casing, near the upper end thereof, is provided a seat, d, which supports a circular metallic plate, e, having a central hole or opening.

E represents a push-bar, which is formed at 60 its lower end with spring - arms F, having hooked ends f, which are adapted to engage the upper ends of the clamping - jaws, which are provided with notches g, to receive said hooked ends. The push-bar E extends through 65 the hole or opening in the plate e, and its upper end is secured in a cap, G, by means of a pin or rivet, h. The said cap G fits within the outer casing, and may be formed with an eye or loop, j, by which it may be suspended 70 from a watch-chain.

Upon the bar E is a spiral spring, i, which bears against the under side of the cap G at one end and against the upper side of the plate e at its other end. It will thus be seen 75 that when the cap G is depressed the clamping-jaws will be spread to receive the key-post. I have provided an elongated slot, k, in the push-bar, and fitting in the same is a pin, l, which is secured at its ends in the upper end of the interior casing. It will thus be seen that the vertical movement of the said push-bar is limited.

I represents a spiral spring which incloses 85 the inner casing and bears against outwardly- extending nibs on the upper end of the same at one end, and against an interior shoulder on the interior of the outer casing at its other end. By this arrangement the outer casing is held in engagement with the teeth of the collar on the lower end of the inner casing. 90

By the construction of key before described it will be observed that the same may be adjusted upon the key - post of any watch, and that the watch may be wound without removing the key from the post or the hand from the key. 95

Having thus described my invention, I claim—

1. In a watch-key, the combination, with an 100

- outer casing, of an inner casing carrying a collar, said collar and outer casing having engaging ratchet-teeth and clamping-jaws for engaging the key-post, as set forth.
- 5 2. In a watch-key, the combination, with an outer casing, of an inner casing carrying a collar, said collar and outer casing having engaging ratchet-teeth, a spring inclosing the upper end of the inner casing and bearing at 10 its upper end against nibs projecting from said casing, and at its lower end against an interior shoulder on the outer casing, as set forth.
3. The combination, with an outer casing, 15 of an inner casing carrying a collar, said collar and outer casing having engaging ratchet-teeth, clamping-jaws in the inner casing, a pin fitting between the same, a spring-actuated push-
- bar having spring-arms to engage the notched upper ends of the clamping-arms, and a spring 20 for holding the outer casing in engagement with the collar on the lower end of the inner casing, as set forth.
4. In a watch-key, the combination, with an outer casing, of the movable inner casing carrying the clamping-jaws, and the ratchet-connection of the inner casing with the outer casing, as set forth.
- In testimony that I claim the foregoing as my own, I have hereto affixed my signature in 25 presence of two witnesses.

MORTON WALLACE GEARY.
